UNITED STATES PATENT OFFICE.

WILLIAM MICHEL, OF COLUMBUS, OHIO.

RAILROAD SIGNAL DEVICE.

No. 863,865.

Specification of Letters Patent.

Patented Aug. 20, 1907.

Application filed April 8, 1907. Serial No. 366,920.

To all whom it may concern:

Be it known that I, WILLIAM MICHEL, a citizen of the United States, and a resident of Columbus, in the county of Franklin and State of Ohio, have made and 5 invented certain new and useful Improvements in Railroad Signal Devices, of which the following is a specification.

My invention relates to an improved railroad signaling device, and more particularly to that kind or character thereof comprising a lever or stop to be located adjacent to the rail or rails to operate a valve located at some convenient place on the locomotive, whereby to blow a whistle in the cab, light an electric lamp, ring a bell, set air brake, or operate some other signaling device 15 when it is attempted by the engineer to pass a semaphore or other signal when set at danger, the object of the invention being to provide an automatic device which shall be simple in construction, easily, readily and cheaply applied, certain in its operations, 20 and so arranged that there will be little danger of its getting out of order.

With these and other ends in view, the invention consists in certain novel features of construction and combinations of parts, as will be hereinafter fully described and pointed out in the claims.

In the accompanying drawings Figure 1 is a plan view of my improved device, a portion thereof being secured to the ties between the rails, and the other portion to the pilot of a locomotive. Fig. 2 is a view in side elevation showing the stop plate in its raised or vertical position. Fig. 3 is a view in perspective of that part of the device located between the rails, and showing the stop plate in its lowered position. Fig. 4 is a longitudinal sectional view of the device shown in 35 Fig. 3.

Referring to the drawings, A—A represent the rails of a railroad track, resting upon the ties B—B. At convenient or selected places along the track, and preferably near the semaphore or other signals, are located the levers or stops to engage with the devices with which the locomotives are equipped, said stops consisting of a shaft 10, located between and lying parallel with two of the ties B—B, held in proper relative positions by the plates C—C bolted thereto, the 45 ends of said shaft being journaled in bearings, each consisting of the bar or plate 11, bolted or otherwise secured to the ties, and the bent or curved plate or bar 12, bolted or otherwise secured to the plate 11. To one extreme end of the shaft 10, and preferably to that 50 end of said shaft which extends beyond the inner rail of the track, is secured one end of the lever 13, the opposite end of said lever having secured thereto one end of the operating rod 14, the latter in turn being connected with a train order signal, block signal, distance

signal, derail, or such other signal or device, as may be 55 desired.

On the shaft 10, and to the right of the center of the track, looking in the direction of the train movement, is mounted the stop plate 15, held in its proper normal position by means of the springs 16—17, coiled around 60 said shaft, one end of said spring 16 being tightly secured to the collar 18 affixed to said shaft, and the opposite end of said spring being secured to one side of said plate 15. One end of the spring 17 is secured to the opposite side of the plate 15, the other end of the 65 spring being tightly secured to the collar 19, also affixed to said shaft, the tendency of these springs being to retain the stop plate 15 in its vertical position, as illustrated in Fig. 4 when the train order signal, block signal, distance signal, or derail is set for stop or danger, 70 and to which signal the stop plate is indirectly connected by the operating rod 14, lever 13, and shaft 10.

It will be understood, of course, that when the block or other signal with which the operating rod 14 is connected, is lowered or moved to a position to 75 indicate safety or clear track, the shaft 10 will be rotated and the stop plate carried by the springs to a lowered or inclined position, as illustrated in Fig. 3 in order that it may be cleared by the coöperating devices with which the locomotive is equipped. By 80 so constructing and arranging the stop plate or lever, it will be seen that should it be struck by ash pan, brake beam, or other portion of the locomotive or cars, the yielding springs 16 and 17 will permit of its being lowered thereby, no matter in which direction 85 the train may be moving, and thereby avoid any injury to or destruction of said plate, or contacting portion of the train.

As before described, the stop plate is preferably located to the right of the center of the track, looking 90 in the direction of the train movement, in order that when in its vertical position it will come in contact with the coöperating devices located at the right of the center of the locomotive pilot, and thereby be operated by a train running in the direction of danger 95 and entirely cleared by a train running in the opposite direction.

To the pipe 20, comprising a part of the train line, is connected the branch pipe 21, the opposite end of which secured to the locomotive pilot, is provided 100 with the valve 22, formed with a hole or opening for the escape or discharge of air. This valve is provided with the lever 23 to which is secured one end of the valve rod 24, the opposite end of said rod passing through and supported in the guide plate 25, also 105 secured to the locomotive pilot, said valve rod being so arranged that it will strike the stop plate 15 when the latter is in its vertical position, a guard plate or

rod 26 being secured to the pilot over and above the end of the rod 24 and extending out beyond the same, in order to protect the end of said valve rod from coming in contact with any obstruction that may be located along the line; said plate or guard 26 being placed in such position on the pilot as to clear the stop plate 15.

From the foregoing it will be understood that when the semaphore or other signal is placed at danger, 10 and the stop plate 15 is in its raised position, said plate will be struck by the end of the valve rod 24 should the engineer fail to act under direction of the signal to stop his train.

While the tension of the springs 16 and 17 is such 15 as to allow the stop plate to yield to the impact of the blow and thereby permit said plate to be lowered, yet it is sufficient to cause the valve rod 24 to operate the valve 22, the effect being to allow of the discharge or escape of the air in the train pipe 20, and cause the 20 brakes to be operated, a whistle blown in the cab, or other visible or audible signal given to the engineer in accordance with the mechanism to which the valve rod may be connected and intended to operate.

While I have shown and described the valve rod 25 24 as operating a valve 22 communicating with the train line 20, it will be evident that such may be arranged to operate any electrical or other signal device, located within the sight or hearing of the engineer, such not being illustrated, as it forms no part of my invention, and to which the invention is in no way limited, it being essential only that the valve rod be so arranged that it will strike the stop plate when the latter is in its vertical position, and be moved or operated thereby, the valve rod in turn operating any 30 signal device or devices which it may be desired to employ.

Having fully described my invention, what I claim as new and desire to secure by Letters Patent, is:—

1. In a device of the character described, the combination with a rotatable shaft rigidly connected to a semaphore or other signal; of a stop plate rotatably mounted upon said shaft and placed in proximity to the track, yielding means connected to the shaft and said stop plate, and adapted to retain said stop plate in its vertical position when the signal is set at danger, a rod secured to the 40 locomotive and adapted to strike the stop plate, and means connected with said rod for operating a signal, substantially as described.

2. In a device of the character described, the combination with a spring actuated stop plate located between 50 the rails, of a rod connecting said stop plate with a semaphore or other signal, whereby said stop plate will be raised when said signal is set at danger and lowered when said signal is set at clear, a valve rod connected with the pilot of a locomotive and projecting forwardly of the said 55 pilot and adapted to strike said stop plate when the latter is in its raised or vertical position, of a valve communicating with the train pipe and connected with and operated by said valve rod, substantially as described.

3. In a device of the character described, the combination with a spring actuated yielding stop plate located 60 between the rails and to the right of the center of the track looking in the direction of the train movement, of means connecting said stop plate with a semaphore or other signal whereby said plate will be in its raised or vertical 65 position when said signal is set at danger, and in its lowered position when said signal is set at clear, a pipe connected with the train pipe and provided with a valve, and a valve rod connected to and operating said valve and adapted to strike said stop plate when the latter is in its 70 raised position, said valve rod being supported by the locomotive pilot and projecting forwardly thereof, substantially as described.

Signed at Columbus, in the county of Franklin, and State of Ohio, this 4th day of April A. D. 1907.

WILLIAM MICHEL.
